RING COOKING UTENSIL FOR HAMBURGER PATTIES

Charles L. Christell, 10 Kathryn St.,
Bellevue, N.J. 07109

Filed June 8, 1971, Ser. No. 151,162

Term of patent 14 years

Int. Cl. D7—02

U.S. Cl. D7—43

Fig. 1.

Fig. 2.

Fig. 3.

FIG. 1 is a bottom perspective view of a ring cooking utensil for hamburger patties showing my new design,
FIG. 2 is a side elevational view thereof,

FIG. 3 is a top plan view.

I claim:

The ornamental design for a ring cooking utensil for hamburger patties, substantially as shown.
